PRODUCTION OF MOTOR FUELS FROM
PETROLEUM OILS

John Weikart, Cranford, N. J., assignor to Standard Oil Development Company, a corporation of Delaware

Application November 30, 1950, Serial No. 198,252

11 Claims. (Cl. 196—49)

1

The present invention relates to improvements in the production of motor fuels and other valuable hydrocarbon products from petroleum oils by a process involving catalytic cracking of relatively high-boiling oils and naphtha reforming. More specifically, the invention pertains to a combination cracking and reforming treatment wherein virgin petroleum oils boiling above the gasoline boiling range are catalytically cracked in dense phase fluid operation to produce cracked gasoline and higher boiling oils, and virgin naphtha mixed with at least a portion of the higher boiling oils formed in the catalytic cracking stage is reformed in the presence of a cracking catalyst suspended in the oil vapors subjected to reforming.

In conventional petroleum refining the crude petroleum is first distilled to produce various virgin distillate fractions which may be converted into motor fuels by suitable refining processes. Of these, catalytic cracking is the most important because it permits the conversion of most of the virgin distillate fractions boiling substantially above the motor fuel range into high octane number gasoline. Catalytic cracking involves an endothermic reaction in the course of which carbon is deposited on the catalyst whereby the activity of the catalyst is rapidly reduced. It is necessary, therefore, to supply substantial amounts of heat to the cracking reaction and to maintain catalyst activity high by carbon removal. These requirements have been met in the most efficient manner by the development of the so-called fluid catalyst technique wherein finely divided catalyst is continuously circulated between a cracking zone and a combustion-regeneration zone. In these two zones the catalyst is maintained in the form of dense highly turbulent solid masses fluidized by upwardly flowing gases and/or vapors to resemble boiling liquids. In the regeneration zone the catalyst is regenerated by carbon combustion and simultaneously heated to a temperature above cracking temperature so that a substantial portion of the heat required in the cracking zone may be supplied as sensible heat of

2

hot regenerated catalyst continuously circulating from the regenerator to the reactor.

It will be appreciated from the above that the production capacity of any given fluid catalytic cracking plant is limited by its carbon burning capacity. This means that only as much feed stock may be cracked as will yield an amount of carbon not in excess of that which may be burned in a regenerator of given design. It also follows that the production capacity of such a plant is partly a function of the carbon-forming tendency of the feed stock, the production capacity being the lower, the stronger the coking tendency of the feed. In the case of fluid type catalytic cracking, this situation is further aggravated by the fact that excessive carbon build-up on the catalyst detrimentally affects the fluidization characteristics of the catalyst.

For these and other reasons, reduction of carbon formation is one of the strongest desiderata in fluid catalytic cracking. One factor complicating the control of carbon formation within desirably low limits is closely connected with the fact that the cracking reaction yields, in addition to motor fuel range and lighter products, substantial proportions of up to about 30-50% based on cracking feed, of higher boiling fractions such as gas oils and heavier materials boiling above 450° F. and up to 800° F. or higher. Most of these materials are of a considerably lower value than motor fuels. Their extensive further conversion into motor fuels is indispensable for a sound economical balance of the process. Recycle of most of these materials to the catalytic cracking stage has, therefore, been widely practiced. However, these relatively heavy cracked products generally called "cycle oils" constitute a cracking feed stock far inferior to virgin gas oils particularly with respect to carbon-forming tendencies, the latter being the stronger, generally, the higher the boiling range of the cycle oil. The permissible amount of oil recycle is, therefore, limited again by the carbon-burning capacity of the system. Furthermore, the capacity of the system for

virgin gas oil rapidly decreases as the amount and boiling range of oil recycled increase.

In spite of these unfavorable aspects, extensive recycle even of the relatively heavy and most marginal cycle stocks has been considered indispensable in most commercial operations as the best and most economic method known for disposing of these materials without excessive losses in valuable motor fuels. It will be readily appreciated that any efficient method permitting a full utilization of the potential motor fuel value of these cycle oils, other than their recycle to the catalytic cracking stage, would greatly increase the virgin gas oil capacity of the system and would thus represent a substantial improvement. In some of its aspects the present invention pertains to an improvement of this type.

It is, therefore, one of the principal objects of the invention to provide means for converting into valuable motor fuels cycle oils obtained in fluid-type catalytic cracking without recycling these cycle oils to the catalytic cracking stage. Other and more specific objects and advantages will appear from the description hereafter in which reference will be made to the accompanying drawing, the single figure of which is a flow diagram illustrating a preferred modification of the invention.

It has been pointed out above that, of the virgin distillates, only those boiling substantially in excess of about 450° F. are suitable for catalytic cracking. The virgin motor fuel range portion such as light and heavy naphthas boiling within the approximate range of 150°-450° F. are too refractory to undergo appreciable conversion at the conditions of catalytic gas oil cracking. As a matter of fact, care must be taken to exclude the presence of these low octane naphtha fractions in the catalytic cracking feed as completely as practically feasible. Any amount of such virgin naphtha passing through the catalytic cracking stage merely acts as a diluent of the high octane naphtha produced by cracking, with respect to the octane rating of the total gasoline recovered from the cracking stage. However, the virgin naphthas likewise require upgrading, particularly with respect to their octane rating to become useful as motor fuels for modern high compression engines. It is, therefore, common practice to subject the virgin naphthas boiling within the approximate range of 150°-450° F. to a so-called thermal reforming treatment at relatively high temperatures of about 1000°-1200° F., relatively high pressures of about 200-1,000 p. s. i. g., and relatively high throughputs of about 3-30 volumes of liquid feed per volume of reactor space per hour (v./v./hr.).

It has now been found that the upgrading of virgin naphthas may be combined with the disposal of catalytic cycle stock in a highly efficient manner so as to reduce or practically eliminate the oil recycle requirements of fluid catalytic cracking processes without any loss in total high-octane gasoline yield based on crude and with a substantial increase in the virgin gas oil cracking capacity of the catalytic cracking stage. In accordance with the present invention, virgin gas oil is subjected to fluid catalytic cracking to produce cracked naphtha and cycle oils, at least a portion of the latter is mixed with virgin naphtha and suitable mixtures of virgin naphtha with catalytic cycle stock, so obtained, are subjected substantially in the vapor phase and in the presence of a finely divided cracking catalyst suspended in the vaporized oil mixture to a

simultaneous naphtha reforming and cycle stock cracking treatment at temperatures of about 1000°-1200° F., pressures of about 300-600 p. s. i. g. and throughputs of about 5-20 v./v./hr. Suitable proportions of naphtha and cycle oil in the mixtures subjected to this treatment fall within the approximate ranges of 20-80 volume percent of naphtha and 80-20 volume percent of catalytic cycle stock, the naphtha concentration of the mixture being the higher, within the range specified, the higher the boiling range of the catalytic cycle stock used. Steam may be added in amounts ranging from about 0 to about 80 mol percent in either stage of the invention, to improve product distribution and octane number of the gasoline. The amount of catalyst which may have a particle size of about 100-400 mesh or smaller may vary from about 2 to about 30 lbs. of catalyst per liquid barrel of mixed feed. While all fluid catalytic cracking products boiling above the motor fuel range may be used together with virgin naphtha in the combination naphtha reforming-cycle oil cracking stage of the invention, the benefits derived from the process are the greater the less valuable the cycle oil for fluid catalytic cracking or for other purposes, i. e., the higher the boiling range of the cycle oil used in the combination reforming and cracking stage. For example, cracked products boiling between the motor fuel range and about 620° F. have normally substantial value as heating oil while the so-called light cycle oil boiling between about 620° and 700° F. may be recycled to the fluid catalytic cracking stage to fair advantage. However, the higher boiling products such as so-called heavy cycle oils are so rich in high molecular weight condensed aromatics as to be merely of marginal utility as a cycle stock for fluid catalytic cracking operations. These oils which may boil between about 700° and 1100° F. are, therefore, particularly suitable for the purposes of the invention. Regarding the virgin naphtha, it is noted that the light cuts boiling up to about 200° or 250° F. are not as readily susceptible to improvements of their octane rating by reforming treatments of the type here involved, as are the heavier cuts boiling from about 200° or 250° F. up to about 450° F. Therefore, a preferred embodiment of the invention provides for the use of mixtures of heavy naphtha boiling within the approximate range of 200°-450° F. with heavy fluid catalytic cycle stock boiling above about 700° F., in the combination naphtha reforming and cycle oil cracking stage of the invention. Preferred mixtures for this type of operation contain about 20-30 volume percent of heavy cycle stock and 70-80 volume percent of heavy naphtha. This ratio corresponds approximately to that at which heavy virgin naphtha and heavy cycle stock are normally produced in commercial combination crude distillation and fluid catalytic cracking plants.

The catalysts used in the fluid catalytic cracking stage and the combination virgin naphtha reforming-recycle stock cracking stage of the invention quite generally may be those known in the art as cracking catalysts such as various synthetic or activated natural clays, particularly various composites of silica gel with alumina and/or magnesia, which may contain certain activating constituents such as boria or certain heavy metal oxides. An excellent catalyst for both process stages of the reaction is a plural synthetic silica-alumina gel combination of about

85-89 wt. percent of SiO_2 and 11-15 wt. percent of Al_2O_3 . A catalyst of comparable quality consists of, say, 20-40 wt. percent MgO gel, the remainder being SiO_2 gel.

When operating in accordance with the present invention substantial improvements are secured over conventional recycling of cycle stock to fluid catalytic cracking and over separate virgin naphtha reforming and catalytic cycle stock cracking under similar conditions, as will appear from the experiments reported below.

A heavy cycle stock obtained in a commercial fluid catalytic cracking plant and virgin heavy naphtha were subjected to several upgrading treatments including once-through fluid catalytic cracking of the cycle stock, high temperature, high pressure, short contact time catalytic cracking, i. e., "susensoid" cracking of the cycle stock alone, thermal and catalytic reforming of naphtha alone, and mixed feed susensoid reforming and cracking of a cycle stock-naphtha mixture in accordance with the invention.

The heavy cycle stock was produced by fluid catalytic cracking of an East Texas wide cut gas oil (50-85% on crude) at 900° F. over natural clay catalyst at an average conversion to 430° F. end point gasoline of 49%. This heavy cycle stock which was used in the experiments had the following inspections:

Gravity, ° API	27
Aniline point, ° F.	178
Initial boiling point, ° F.	544
End point, ° F.	874
Sulfur, wt. percent	0.31
Carbon, wt. percent	0.13
Viscosity (Say. Univ. at 100° F.) sec.	63.0

The catalyst employed in all experiments was a commercial synthetic mixed gel SiO_2 - Al_2O_3 catalyst consisting of about 87% SiO_2 and 13% Al_2O_3 brought to equilibrium activity by previous extensive use in a commercial fluid catalytic cracking plant. It was adjusted to a content of 80+ microns particles of about 30%.

The essential operating conditions and results of the catalytic cracking experiments carried out with heavy catalytic cycle stock alone are summarized in Table I below:

TABLE I

Catalytic cracking of catalytic heavy cycle stock

Process	Once-Through		Once-Through Fluid

^a Maximum severity limited by coking.

^b Conditions for maximum gasoline yield.

^c Volumes of cold oil per hour per volume of coil section maintained above 800° F.

^d Pounds of oil per hour per pound of catalyst.

The above data show that once-through fluid cracking of the cycle stock at severe conditions suitable for maximum gasoline yield gives about the same amount of gasoline as susensoid cracking in the absence of steam, but less than susensoid cracking in the presence of steam. The octane ratings of the gasoline obtained by fluid cracking is substantially greater than that obtained by susensoid cracking. However, the excessive carbon formation of the fluid operation makes this method unattractive for commercial application.

Operating conditions and results of thermal and susensoid catalytic naphtha reforming experiments are summarized in Table II. The naphtha used in these experiments was a Mid-Continent-Louden mixed naphtha (150°-400° F. boiling range).

The data of Table II demonstrate that catalytic susensoid reforming of naphtha affords no appreciable advantages over thermal naphtha reforming with respect to gasoline yield and quality.

In the remaining experiments oil mixtures containing 25 vol. per cent of heavy naphtha and 75 vol. per cent of heavy cycle stock were subjected to mixed-feed "susensoid" naphtha reforming and cycle stock cracking in accordance with the invention.

The heavy naphtha used in these experiments was a West Texas virgin heavy naphtha of the following inspections:

Gravity, ° API	49.5
Aniline Point, ° F.	119
Initial boiling point, ° F.	228
Final boiling point	397
Reid Vapor Pressure, p. s. i.	0.2
ASTM Motor O. N., clear	41.0
CFR Research O. N., clear	42.2

The cycle stock was that used to obtain the data of Table I. The conditions and results of these experiments are summarized in column C of Table III below. The results obtained are compared with the total overall results for yields and gasoline quality calculated from segregated operations on the individual stocks as summarized in columns A and B of Table III. The conditions of naphtha reforming of the segregated runs in columns A and B are typical for present day commercial operation. The conditions used for segregated cycle stock cracking are those required for maximum gasoline yields.

¹ W./hr./w.

From the data of column C of Table III it appears that the gasoline yield passes through a maximum at about 1077° F. A further increase in temperature merely cracked gasoline to gas without affecting the yield of product boiling above 430° F. A temperature range of about 1070°-1085° F. is, therefore, preferred for this stage of the invention. When operating at these intermediate temperatures, gasoline yields of or exceeding 53 vol. per cent may be obtained at a Research Octane number level of about 82. This result is clearly superior to that of the best segregated process including "suspensoid" cracking of cycle stock alone even in the presence of steam as is shown in column A of Table III. The reasons for this improvement in results are not fully understood. It can not be explained by the effect of the catalyst on the naphtha because thermal and suspensoid catalytic naphtha reforming give equivalent gasoline yield/octane relationships as shown by the experiments of Table II. However, it is possible that the naphthenic hydrocarbons in the naphtha may donate hydrogen by means of hydrogen transfer reactions to the high boiling condensed heavy hydrocarbons of the cycle stock and promote cracking to gasoline range compounds.

The segregated process involving fluid cycle stock cracking (column B) enjoys a marked advantage with respect to gasoline octane rating. However, gasoline yields are lower than those shown in column C for the process of the invention. This drawback, in combination with the excessive carbon formation, out-weighs the octane advantage in commercial operation.

Having set forth its objects and general nature, the invention in its practical aspects will be best understood from the subsequent more detailed description read with reference to the drawing.

Referring now to the drawing, the system illustrated therein essentially comprises a crude distillation section 1, 21, a fluid catalytic cracking section 40, 50 and a suspensoid processing section 84, the functions and coaction of which will be presently described using the production of motor fuels from a West Texas crude oil as an example. It should be understood, however, that the sys-

tem may be employed for the conversion of other types of crude oil in a substantially analogous manner.

In operation, a typical West Texas crude oil supplied through line 1 is heated in furnace 3 to about 500°-800° F. and supplied through line 5 to a crude still 7 operated substantially at atmospheric pressure. The crude may be fractionated in still 7 into several fractions comprising a normally gaseous fraction (about 1 wt. per cent on crude) withdrawn as overhead through line 9; a light naphtha having an end boiling point of about 200°-250° F. (about 8-13 vol. per cent on crude) withdrawn via line 11, a heavy naphtha having a boiling range of about 200° or 250°-430° F. (23-18 vol. per cent on crude) withdrawn via line 13, a heating oil boiling between about 430° and 620° F. (about 21 vol. per cent on crude) recovered via line 15, and a reduced crude containing all constituents boiling above about 620° F. (about 48 vol. per cent on crude) withdrawn through line 17. The light products recovered via lines 9 and 11 may be further treated by alkylation and other refining treatments to produce high quality motor fuels or blending stock in any conventional manner. The heating oil recovered via line 15 may be finished in a conventional manner and then passed to storage.

The reduced crude withdrawn through line 17 may be passed via line 19 to a conventional vacuum still 21 to be separated therein into pitch (about 14% on crude) recovered through line 23 and gas oil of about 620°-1100° F. boiling range (about 34 vol. per cent on crude) taken overhead via line 25 to be passed via line 27 by means of pump 28 to the fluid catalytic cracking stage as virgin gas oil feed for this stage. Instead of using a vacuum still in the manner just described, atmospheric pressure still 7 may be so operated that in addition to the fractions withdrawn through lines 9, 11, 13 and 15 a gas oil boiling within the approximate range of 620°-950° F. (25 vol. per cent on crude) is withdrawn via line 29 and passed to line 27 while the bottoms withdrawn via line 17 (about 22 vol. per cent on crude) may contain all constituents boiling above 950° F. and serve as a fuel oil or a feed stock for

conventional coking or visbreaking operations. In any case, the virgin gas oil in line 21 and the virgin heavy naphtha in line 13 will be treated in accordance with the invention as follows.

The gas oil substantially at the temperature at which it is produced in still 7 or vacuum still 21 is passed from line 27 into line 33 wherein it is mixed with hot regenerated cracking catalyst supplied from regenerator standpipe 35 as will appear more clearly hereinafter. The catalyst which may be a silica-alumina gel composite (87% SiO_2 -13% Al_2O_3) having a fluidizable particle size distribution averaging about 40-70 microns may be supplied from standpipe 35 at a temperature of about 1000°-1200° F. in amounts of about 5-35 lbs. per lb. of gas oil flowing in line 33. If desired, about 5-20 lbs. of steam per lb. of gas oil may be added from line 37 to line 33.

The dilute suspension of catalyst in gas oil vapors passes upwardly through line 33 into a conical distributing device 39 arranged in the bottom portion of reactor 40. The suspension entering reactor 40 at a suitable cracking temperature of about 800°-1000° F. forms therein a highly turbulent solids mass M_{40} resembling a boiling liquid having an apparent density of about 20-40 lbs. per cu. ft. separated by an interface L_{40} from a superimposed dilute phase. Linear superficial vapor velocities in mass M_{40} of about 0.3-3 ft. per second are suitable for this purpose. Cracking may take place in mass M_{40} at about 900°-1000° F., 0-20 p. s. i. g. pressure and oil throughputs of about .3-5 lbs. of gas oil per hour per pound of catalyst in mass M_{40} .

Spent catalyst passes continuously from mass M_{40} into the annular space between cone 39 and the walls of reactor 40 and thence into reactor standpipe 42 substantially at the rate of catalyst supply via line 33. Steam, flue gas or other inert gas may be admitted through a plurality of taps t to strip and aerate the catalyst withdrawn from mass M_{40} . Standpipe 42 feeds into gas line 44 wherein the spent catalyst is picked up by air or other oxidizing gas containing sufficient oxygen to remove, in the form of carbon oxides, substantially all the carbon deposited on the catalyst in reactor 40.

The suspension of catalyst in oxidizing gas is passed from line 44 through the conical bottom portion 46 of regenerator 50, if desired, through a perforated plate 48, at flow conditions adapted to form in regenerator 50 a fluidized mass M_{50} having a level L_{50} , similar to mass M_{40} . The composition of the oxidizing gas is so adjusted that mass M_{50} is maintained at a temperature of about 1000°-1200° F., preferably 1050°-1150° F., and most of the carbon is burned off at substantially atmospheric pressure. Flue gases pass overhead from level L_{50} , preferably through a gas-solids separator such as cyclone 52 to be removed via line 54 for any desired purpose. Separated catalyst may be returned via dip-pipe 56 to mass M_{50} or discarded via line 58. Make-up catalyst may be supplied via line 37, suspended in steam. In order to prevent catalyst overheating, particularly in the case of excessive carbon formation in reactor 40, suitable cooling devices (not shown) may be imbedded in mass M_{50} or catalyst from mass M_{50} may be continuously circulated through a suitable separate cooling device (not shown) and returned to mass M_{50} at a lower temperature, all in a manner known per se. Regenerated catalyst leaves mass M_{50} through standpipe 35 to enter line 33 as described above. Small amounts

of an aeration and/or stripping gas may be injected into standpipe 35 via taps t .

Returning now to reactor 40, cracked vapors containing small amounts of entrained catalyst are passed overhead from level L_{40} through a suitable gas-solids separation system including one or more cyclones 60 from which separated catalyst may be returned to mass M_{40} via dip-pipe 62. Cracked products of reduced solids content are passed via line 64 to fractionator 66 which may be operated as follows. An overhead fraction containing about 10-25 vol. per cent on crude of motor fuel range hydrocarbons and about 1-4 wt. per cent on crude of hydrocarbon gases may be recovered via line 68 to be passed to conventional finishing equipment (not shown). Product heating oil having a boiling range of about 430°-620° F. and amounting to about 5-10 vol. per cent on crude may be withdrawn through line 70 and passed to storage. The products boiling above about 620° F. and amounting to about 5-10 vol. per cent on crude represent "cycle oils." They may be recovered from fractionator 66 in three conventional fractions including a light cycle oil having a boiling range of about 620°-700° F. (about 1-3 vol. per cent on crude) withdrawn via line 72, a heavy cycle oil boiling between about 700° and 900° F. (about 3-5 vol. per cent on crude) withdrawn through line 74 and bottoms boiling above 900° F. (about 3-5 vol. per cent on crude) withdrawn via line 76.

At least the total bottoms fraction in line 76 and most of the heavy cycle oil in line 74, being cycle stock of highly marginal quality, are passed to line 78 for further treatment in accordance with the invention. Any desired portion of the light cycle oil in line 72, say about 10-100%, may be recycled to reactor 40 via lines 80, 82 and 33, by means of pump 83. Any remainder, or if desired, the total light cycle oil in line 72, may be likewise added to line 78 for further treatment as will be presently described. That portion of the heavy cycle oil in line 74 which is not passed to line 78 may be recycled via line 82. The fractionator bottoms in line 76 contain as a sludge the entire catalyst carried out of cyclone 60 with the oil vapors. This catalyst, which normally has a particle size of less than 40 microns and which may amount to about 1-1 lb. per gallon, may be used to full advantage in the subsequent "suspensoid" treating stage of the invention.

The combined cycle oils containing suspended cracking catalyst are passed by means of pump 79 through line 78 wherein they are mixed preferably with the heavy virgin naphtha fraction produced in still 7 and supplied through line 13 by means of pump 14. Since the virgin naphtha requirement for the "suspensoid" stage of the invention decreases as the volatility of the catalytic cycle oil increases, the amount of virgin naphtha available in line 13 will be sufficient for the purposes of the invention no matter what proportion of the light cycle oils in lines 72 and 74 is passed on through line 78.

The mixture of recycle stock and virgin heavy naphtha, containing about 20-80 vol. percent of the latter, depending on the disposition of the cycle oils, is passed to "suspensoid" reactor coil 84 arranged in furnace 86. If desired, additional silica-alumina cracking catalyst of about 100-400 mesh or finer may be added through line 88, preferably suspended in steam amounting to about 0.5-5 vol. percent of steam on total oil in line 78 so as to maintain a catalyst/oil ratio in reactor

84 of about 2-30 lbs., preferably about 5-15 lbs. per bbl. of oil supplied thereto. Reaction conditions in coil reactor 84 may include temperatures of about 1000°-1200° F., preferably 1070°-1085° F., pressures of 100-600 p. s. i. g., preferably 300-600 p. s. i. g., and throughputs of about 5-20 v./v./hr., preferably about 7-12 v./v./hr.

The reaction products are withdrawn from reactor 84 through line 90 and may be passed to a cyclone separator 92 from which most of the catalyst may be recovered via line 94 for reuse in the system, if desired, after regeneration. The product vapors leaving cyclone 92 via line 96 may be expanded to a pressure of about 100 p. s. i. g. or lower by means of valve 97 and quenched to a temperature of about 600°-800° F. by a cold gas oil (430°-700° F.) introduced via line 98.

The mixture may then be discharged via line 100 into fractionator 105 wherein it may be fractionated to yield final products as follows. A combined light ends and motor fuel fraction boiling up to about 430° F. (about 20-30 vol. percent on crude) may be recovered through line 108 to be treated as described with reference to the overhead of fractionator 66 in line 68. Heating oil boiling within the range of 430°-620° F. may be recovered through line 110 and may be combined with the products recovered through lines 15 and/or 70. Bottoms boiling above 620° F. (about 3-8 vol. percent on crude) may be recovered via line 112 freed of any suspended catalyst by filtration or the like and used for any desired purpose, for example as fuel oil or a speciality product (for carbon black manufacture).

The system illustrated in the drawing permits of various modifications. For example, fractionators 66 and 105 may be so operated that separate streams of normally gaseous products and motor fuel range hydrocarbons are recovered. Instead of removing three separate streams of cycle oils from fractionator 66, the products boiling above 620° F. may be removed in a single bottoms stream or in more than three fractions, depending on the character of the crude oil fed to the system. Similarly, fractionator 105 may be operated to yield more than one fraction of the products boiling above 620° F. In place of coil reactor 84 other types of reactors known in oil cracking may be used, such as tube and tank arrangements in which the oil is heated in a fired coil and discharged into a tank, conversion taking place in either the coil or the tank, or both.

The above description and exemplary operations have served to illustrate specific embodiments of the invention but are not intended to be limiting in scope.

What is claimed is:

1. In the process of producing motor fuels from crude petroleum which comprises subjecting crude petroleum to distillation to produce a heavy virgin naphtha fraction boiling between about 200 and 450° F. and a gas oil fraction, subjecting said gas oil fraction to catalytic cracking in a cracking zone in the presence of a dense turbulent fluidized mass of subdivided cracking catalyst at motor fuel producing conditions, withdrawing catalyst from said mass, regenerating said withdrawn catalyst in a regeneration zone by a combustion reaction to remove carbonaceous deposits and reheat the catalyst, returning hot regenerated catalyst from said regeneration zone to said mass, withdrawing cracked products from said cracking zone, fractionating said cracked

products in a fractionation zone, withdrawing from said fractionation zone a fraction containing motor fuels and a cycle oil fraction boiling above about 700° F., the improvement which consists of combining at least a major portion of said cycle oil fraction with at least a portion of said heavy virgin naphtha fraction to produce a mixture containing about 20-80 vol. percent of virgin naphtha, passing said mixture substantially in the vapor phase through a narrowly confined path at temperatures of about 1000°-1200° F., pressures of about 300-600 p. s. i. g. and residence times corresponding to throughputs of about 5-20 v./v./hr. in the presence of finely divided cracking catalyst suspended in said mixture in a proportion of about 2 to 30 pounds of catalyst per liquid barrel of mixed feed, withdrawing reaction products from said path and recovering motor fuels from said reaction products.

2. The process of claim 1 in which said mixture consists of about 20-30 vol. percent of said cycle oil fraction and of about 70-80 vol. percent of said naphtha fraction.

3. The process of claim 1 in which a fraction boiling within the approximate range of 620°-700° F. is withdrawn from said fractionation zone and recycled to said cracking zone.

4. In the process of producing motor fuels from crude petroleum which comprises subjecting crude petroleum to distillation to produce a light virgin naphtha fraction, a heavy virgin naphtha fraction boiling between 200 and 450° F., and a gas oil fraction, subjecting said gas oil fraction to catalytic cracking in a cracking zone in the presence of a dense turbulent fluidized mass of subdivided silica-alumina cracking catalyst at motor fuel producing conditions, withdrawing catalyst from said mass, regenerating said withdrawn catalyst in a regeneration zone by a combustion reaction to remove carbonaceous deposits and reheat the catalyst, returning hot regenerated catalyst from said regeneration zone to said mass, withdrawing from said cracking zone a dilute suspension of fines of said cracking catalyst in cracked product vapors, passing said suspension to a fractionation zone, withdrawing from said fractionation zone a motor fuel fraction, a cycle oil fraction boiling between about 620 and 700° F., and a bottoms fraction boiling between about 700 and 1100° F., and containing said catalyst fines, the improvement which consists of combining at least a portion of said fines-containing bottoms fraction with at least a portion of said heavy virgin naphtha fraction to produce a mixture containing about 20 to 80 volume percent of said heavy virgin naphtha and about 2 to 30 pounds of catalyst per barrel of mixed liquid feed, passing the mixture so obtained substantially in the vapor phase through a narrowly confined path at temperatures of about 1070°-1085° F., pressures of about 300-600 p. s. i. g. and residence times corresponding to throughputs of about 5-20 v./v./hr. in the presence of said catalyst fines suspended in said mixture, withdrawing reaction products from said path and recovering motor fuels from said reaction products.

5. The process of claim 4 in which said catalyst fines have a particle size of less than 40 microns diameter.

6. The process of claim 4 in which said cracking catalyst is a synthetic silica-alumina composite containing about 11-15 wt. per cent of alumina.

7. The process of claim 4 in which said mixture passing through said path contains about 25

volume percent of said heavy virgin naphtha and about 10 lbs. of catalyst per liquid bbl. of mixed feed, and in which the pressure in the confined path is about 350 p. s. i. g. and the throughput about 9 v./v./hr.

8. The process of claim 7 in which extraneous subdivided catalyst is added to said mixture.

9. The process of claim 4 in which said cycle oil fraction boiling between about 620° and 700° F. is withdrawn from said fractionation zone and re-cycled to said cracking zone.

10. The process of claim 4 in which said mixture contains said virgin heavy naphtha and said bottoms in the ratio in which the same are produced in said process.

11. The process of claim 4 in which steam is added to said path.

JOHN WEIKART.
